UNITED STATES PATENT OFFICE

FREEMAN F. HEATER, OF SEATTLE, WASHINGTON

DESIGN FOR AN AVIATOR'S HELMET

Application filed July 2, 1929. Serial No. 31,928. Term of patent 14 years.

To all whom it may concern:

Be it known that I, FREEMAN F. HEATER, a citizen of the United States, residing at Seattle, in the county of King and State of Washington, have invented a new, original, and ornamental Design for Aviators' Helmets, of which the following is a specification, reference being had to the accompanying drawing, forming part thereof.

Figure 1 is a three-quarters front perspective showing my new design in use, the stippling showing a contrast in coloring.

Figure 2 is a rear view of the same, the stippling representing a contrast in coloring.

The characteristic feature of the design resides in the central panel of the helmet which is unobstructed at its longitudinal center and gradually broadens from the front to the crown portion and diminishes in width from said crown portion to the back.

I claim:

The ornamental design for an aviator's helmet, as shown and described.

FREEMAN F. HEATER.
